UNITED STATES PATENT OFFICE.

THOMAS H. DODGE, OF NASHUA, NEW HAMPSHIRE.

IMPROVEMENT IN MARINE SIGNALS.

Specification forming part of Letters Patent No. 9,384, dated November 9, 1852.

To all whom it may concern:

Be it known that I, THOMAS H. DODGE, of Nashua, in the county of Hillsborough and State of New Hampshire, have invented certain new and useful Improvements in Night Signal-Lights for Vessels at Sea and for other Purposes; and I do hereby declare the following is a full, clear, and exact description of the same, reference being had to the accompanying drawings, forming part of this specification, in which—

Figure 1 is a perspective view of one of my improved signals. Fig. 2 is a vertical longitudinal section of the same. Fig. 3 is a plan or top view of the compass, pulley, and cords for raising and lowering the lamp.

The same letters of reference in each of the several figures indicate corresponding parts.

The nature of my invention consists in a hollow pyramidal-shaped box having a number of different-colored indicating-glass windows on all of its sides from the top to the base, and also having a lamp with suitable reflectors placed within the same, which is made to move up and down on a pedestal in the hollow pyramidal-shaped box when it is desired to change the color of the signal by means of a horizontal pulley and a cord, which is passed round the same and has its ends secured fast to the top and bottom of the pedestal in such a manner that when the pulley is turned in one direction the pedestal will be elevated and when moved in the contrary direction the lamp will be lowered. The top surface of the said pulley may have the courses E, W, N, S, &c., marked out on it, so that when it is desired to bring the lamp directly opposite the red signals at the top, which may indicate "north," the operator will know exactly how far to turn the pulley to elevate the lamp to the desired position, for it will be seen that the operator in this case has only to move the pulley round until the letter N points opposite to north or any other set point, and thereby bring the lamp directly opposite the red signals on all the sides of the box, the light from which will be reflected on the red windows by suitable reflectors, thereby indicating to vessels at a distance and in different locations that her course is north. If the course of the vessel should be northeast, the pulley must in like manner, as

before, be turned until the letters N E occupy the position vacated by N. This will bring the lamp opposite the mixed-colored glass windows, yellow and red, the light in like manner, as before, being reflected on the yellow and red glasses on all the sides of the box. The fact that the vessel is moving in a northeast course will be made known to vessels at a distance, no matter what may be their position, and consequently running into or coming in contact with each other when it is very dark will be very effectually prevented.

To enable others skilled in the art to make and use my invention, I will proceed to describe its construction and operation.

A represents the base of the signal-box, and B is the hollow pyramidal or other suitable shaped signal-box.

C C C C represent a number of colored glass lights arranged on all sides of the box B from the top to the base. Some of these lights C, it will be seen, are mixed, being composed of half red and yellow, or half blue and green, and so on, as may be thought best. The object in mixing the colors is to make them more attractive or distinct, so that they may be seen at a greater distance by vessels. By placing these lights of glass of different colors or shades on all sides of the vessel her course may be known by crews of other vessels at a distance, whether they be situate behind or before her, or on her sides, and collisions may thereby with certainty be prevented, and in case of distress assistance might be obtained in a very short time by continually raising and lowering the lamp or changing the signal from one color to another.

D is the lamp, which rests on the end of a pedestal E, with which it is made to rise and fall in the manner substantially as shown in Fig. 2.

E is a reflector placed above the lamp (and another one may be placed on the upper surface of the lamp) for throwing the light full upon the colored-glass windows immediately opposite the flame in a horizontal line. There may be partitions or slides so arranged underneath and above the flame that there will be no possible chance of the light being seen through any of the windows above or below the one opposite the light or lamp unless the lamp be lowered below the lower partition or

slide, or raised above the upper partition, and be brought directly opposite the window above or below the said slide.

G is a horizontal pulley supported by a standard S and having the courses E W N S marked out on its top surface. This pulley is seen clearly in Fig. 3. A cord H H' passes round and in the groove of the pulley and is secured fast near the center of its length in the same, and has one of its ends I passed over the barrel K, and then secured to the lower part of the sliding pedestal E, and the other end J passed under the barrel K and secured to the upper part of the pedestal in the manner shown in Fig. 2. By moving this pulley round in one direction it will elevate the pedestal E, and by turning it in the opposite direction the pedestal and lamp will be lowered in the manner shown in Fig. 2 in dotted lines. The lamp can thus be always raised and lowered so as to bring it always opposite the colored-glass windows in a line with the lamp or light which indicate the vessel's course.

K is a small horizontal barrel over which the cord is guided, and L L are small pillars for sustaining and keeping the cord properly adjusted when in motion.

M are ventilators in the top and sides of the box B.

N is a door through which the lamp is taken from and inserted into the box.

This apparatus can be made to answer very well as a night-signal for railroads to indicate whether the switches are in their proper position and whether there is any danger

ahead by simply placing one of these signal-boxes on the top of a pole and then raising and lowering a lamp from one color to the other to indicate "danger" or "safety" by means of a cord or chain passing over a pulley at the top of the pole and connected to a windlass on which it winds or is wound as the lamp is elevated.

As this signal may be operated in many different ways from that shown, either by cord and pulley and rack and pinion, &c., and as it can be constructed somewhat differently from that shown—for instance, the colored lights may be made round or like a circular disk, and the box could be made with six, eight, or more sides—I therefore do not confine myself to the precise construction and operation described and shown.

Having thus fully described the nature and operation of my invention, I will state what I claim as new and desire to secure by Letters Patent:

Placing the lamp on a movable pedestal E or its equivalent inside the many-sided signal-box B and raising and lowering the same from one colored glass to another by means of the cord H H' and pulley G or their equivalents, the whole being constructed, arranged, and operating in connection with a signal B C in the manner and for the purposes substantially as herein described.

THOMAS H. DODGE.
